H. E. SHREEVE,
VACUUM TUBE SOCKET,
APPLICATION FILED MAY 20, 1916.

1,325,865.

Patented Dec. 23, 1919.

Inventor:
Herbert E. Shreeve
by *D. C. Munro, Atty.*

UNITED STATES PATENT OFFICE.

HERBERT E. SHREEVE, OF WYOMING, NEW JERSEY, ASSIGNOR TO WESTERN ELECTRIC COMPANY, INCORPORATED, OF NEW YORK, N. Y., A CORPORATION OF NEW YORK.

VACUUM-TUBE SOCKET.

1,325,865.

Specification of Letters Patent. Patented Dec. 23, 1919.

Application filed May 20, 1916. Serial No. 98,770.

To all whom it may concern:

Be it known that I, HERBERT E. SHREEVE, a subject of the King of Great Britain, residing at Wyoming, in the county of Essex and 5 State of New Jersey, have invented certain new and useful Improvements in Vacuum-Tube Sockets, of which the following is a full, clear, concise, and exact description.

This invention relates to a socket for vacuum tubes, and in particular to vacuum tubes such as the audion, in which a plurality of electrodes comes from said tube, and with which electrodes intimate connection must be made for various circuits. Its purpose is 15 to construct a socket which will be convenient for use and effective in making such contacts as are required.

The invention will be better understood by reference to the following specification 20 and the accompanying drawing, in which Figure 1 shows a socket designed according to this invention in combination with one form of audion tube. Fig. 2 shows a view from below of the socket shown in Fig. 1. 25 Fig. 3 is a plan view of an element comprising two sockets as one unit, Fig. 4 is a section on the line 4—4 of Fig. 3, and Fig. 5 is a perspective view of the spring contact element or unit used throughout Figs. 1 to 4.

30 Referring in particular to Fig. 1, 10 represents a casting of brass or other suitable metal, of which 11 is the base, and 12 the socket proper, into which socket a vacuum tube with suitable terminals may be inserted, 35 as hereinafter described. Secured to the bottom of the base 11 and at one side is a spring contact unit, such as is shown in Fig. 5, this unit comprising a strip of insulating material 13 with spring elements 15, 16, 17 and 18, secured thereto in any suitable manner. One method of securing these springs to the insulating strip is shown in Figs. 2 and 5, Fig. 5 showing at 30 depressed bolts which, in connection with the nuts 31 shown 40 in Fig. 2, hold the respective spring elements in a rigid position with respect to the strip 13, and to assist in this, it will, in general, be desirable to place these spring elements in grooves, as shown in the various figures.

45 The spring contact unit is secured rigidly to the base plate 11 by means of screws 20 engaging with suitable nuts 21 shown in Fig. 2.

The various spring members 15 to 18 project forward, and to such an extent and 55 manner that their terminals 25, 26, 27 and

28 are suitably disposed below the opening of the socket member 12 to make contact with the terminals of the vacuum tube to be used in connection therewith. In this particular case, these terminals are shown as forming 60 respectively the corners of a square, the center of which square falls upon the axis of the socket 12.

For convenience, it may be desirable to insert a plate 32 with suitable numerals or designation characters, such as shown in Figs. 1 and 3, by means of which the several terminals may be readily recognized one from the other. Around the base plate 11, or a portion thereof, is placed a rim 33 of such a 70 height as to give free motion to the spring elements.

The socket thus far described is particularly adapted for use in combination with a form of audion tube shown in Fig. 1. This 75 tube 40 comprises an evacuated vessel within which are placed a filament, a grid and a plate element. For ordinary use, such a tube requires four terminals, two being connected with the filament, one with the grid, 80 and one with the plate. In Fig. 1, there is shown a circular piece of insulating material 44 to which the four terminals are secured. The grid terminal is shown at 45, the filament terminals at 46 and 47, and the plate 85 terminal at 48, and in this particular tube, these terminals 45 to 48 are arranged at the corners of a square. The tube 40 is supplied with a collar 49 secured to the bulb by any suitable sealing material, and the collar 49 90 is of such dimensions as to fit snugly into the socket 12. This collar 49 with the insulation member 44 will be spoken of as a "block." On said collar 49 is placed a small pin 50, which engages with a slot 51 in the 95 member 12, forming thereby a bayonet joint. The pin 50 and the slot 51 are so positioned with respect to each other that the terminals 45 to 48 will make contact with the spring terminals 25 to 28, respectively, and these 100 terminals 45 to 48 are made of such length that a suitable contact pressure is obtained with the springs 25 to 28, respectively.

Figs. 3 and 4 show a somewhat modified structure in which, in place of the casting 10, 105 there is used a plate member 60 serving as a base, this being of sheet metal or other suitable flat material. Sections 62 of brass tubing or other suitable metal are then secured to the plate member 60, as shown in detail 110

in Fig. 4. The internal dimensions of the tube 62 are so chosen as to make a close fit with the collar 49 of the vacuum tube to be used. In Fig. 3, two such socket members 62 are shown, but it is apparent that by increasing the length of the plate 60 any number of such socket members may be used. Adjacent to each of said sockets is placed one of the spring contact units shown in Fig. 5, this 10 contact unit being secured in the proper position and in exactly the same manner as described in connection with Figs. 1 and 2. Any desired method may be used for elevating the member 60 sufficiently above its support 15 so as to give free motion to the spring contact element, and in this case, there are shown small feet 64. If desired, these feet may consist of brass tubing, as shown in the figures, affording thereby convenient means 20 for screwing the whole socket member to any suitable support.

What is claimed is:

1. In a vacuum tube set, the combination with a socket, of a vacuum tube having a 25 block attached thereto and a plurality of electrodes secured to said block and arranged adjacent to each other, the socket comprising a base portion having an opening therein, a tubular portion fitting in said opening and 30 arising therefrom, a plurality of contact springs secured to but insulated from said base, said springs projecting under the base portion and beneath said opening and so disposed as to make contact with the respective 35 electrodes of the vacuum tube in a prearranged manner.
2. In a vacuum tube set, the combination with a socket, of a vacuum tube having a block attached thereto and a plurality of 40 electrodes secured to said block, said socket comprising a base, a socket member attached to said base, a contact unit secured to the under side of said base, said unit comprising a strip of insulation and a plurality of 45 contact springs projecting under the socket opening and so disposed as to make contact with the respective electrodes of the vacuum tube in a prearranged manner.

3. In a vacuum tube set, the combination 50 with the neck of a vacuum tube having four electrodes, of a socket, the socket comprising a base, a socket member attached thereto, and a contact unit secured to the under side of said base, said unit comprising a strip of insulation and four contact springs projecting under the socket opening and so disposed as to make contact with the four electrodes of the tube in a prearranged manner.

4. In a vacuum tube set, the combination 60 with a socket, of a vacuum tube having a block attached thereto, a plurality of electrodes secured to said block and arranged adjacent to each other, said socket comprising a base and a socket member attached 65 thereto, a plurality of contact springs se-

cured to but insulated from said base, certain ends of said springs projecting under the socket opening and so disposed as to make contact with the respective electrodes of the vacuum tube in a prearranged manner, the opposite ends of said springs projecting beyond the lateral edges of said base, whereby external circuit connections may be readily made. 70

5. In a vacuum tube set, the combination 75 with a socket, of a vacuum tube having a block attached thereto and a plurality of electrodes secured to said block, said socket comprising a base and a socket member attached thereto; a contact unit secured to the underside of said base, said unit comprising a strip of insulation and a plurality of contact springs projecting beyond the lateral edges of said insulation and under the socket opening, and so disposed as to 80 make contact with the respective electrodes of the vacuum tube in a prearranged manner, portions of said springs projecting beyond the lateral edges of said base whereby external circuit connections may be readily 85 made.

6. In a vacuum tube set, the combination 90 with a socket, of a vacuum tube having a block attached thereto and a plurality of electrodes secured to said block, said socket comprising a base, a socket member attached thereto, a contact unit secured to the underside of said base, said unit comprising a strip of insulation and a plurality of contact 95 springs projecting under the socket opening and so disposed as to make contact with the respective electrodes of the vacuum tube in a prearranged manner, said insulation having grooves therein, whereby said contact springs may be rigidly held in place. 100

7. In a vacuum tube set, the combination 105 with a socket, of a vacuum tube having a block attached thereto, said block comprising a collar surrounding the lower portion of said tube and an insulation piece substantially closing the lower end of said collar and attached thereto; a plurality of electrodes attached to said insulation piece, said socket comprising a base having a socket opening and a socket member attached to said base 110 over said opening, a plurality of contact springs secured to but insulated from said base, said springs projecting under the socket opening and so disposed as to make contact with said electrodes in a prearranged manner. 115

8. A socket adapted to receive the electrodes of a vacuum tube, comprising a flat base and a tubular portion integral therewith and arising therefrom, a contact unit 120 secured to the under-side of said base, said unit comprising a strip of insulation and a plurality of substantially parallel contact springs attached to said insulation, said springs projecting under the tubular portion, 125 130

portions of said springs projecting beyond the lateral edges of said base, whereby external circuit connections may be readily made.

- 5 9. In a vacuum tube set the combination with a socket, of a vacuum tube having a block attached thereto and three electrodes secured to said block, said socket comprising a base, a socket member attached to said base, a contact unit secured to the under side of said base, said unit comprising a strip of insulation and three contact springs projecting under the socket opening and so disposed as to make contact with the respective electrodes of the vacuum tube in a prearranged manner.
- 10
- 15

10. In a vacuum tube set, the combination with a socket, of a vacuum tube having a plurality of electrodes attached thereto, the socket comprising a base portion having an 20 opening therein, a tubular portion fitting in said opening and arising therefrom, a plurality of contact springs secured to said base portion at a point distant from said opening, said springs extending under the base 25 portion to a point beneath said opening and so disposed as to make contact with the respective electrodes in the vacuum tube in a prearranged manner.

In witness whereof, I hereunto subscribe 30 my name this 18th day of May, A. D., 1916.

HERBERT E. SHREEVE.
